(57)

CLAIM

The ornamental design for a gaming machine island, as shown and described.

DESCRIPTION

FIG. 1 is a front perspective view of a gaming machine island showing the new design;

FIG. 2 is a front view thereof;

FIG. 3 is a rear view thereof;

FIG. 4 is a right side view thereof;

FIG. 5 is a left side view thereof;

FIG. 6 is a top plan view thereof; and,

FIG. 7 is a bottom plan view thereof.

In these drawings, broken lines illustrate unclaimed environmental features and form no part of the claimed design.

1 Claim, 7 Drawing SheetsRelated U.S. Application Data

a division of application No. 29/735,520, filed on May 21, 2020, now Pat. No. Des. 954,829.
